UNITED STATES PATENT OFFICE.

WILLIAM G. NAGEL, OF TOLEDO, OHIO, ASSIGNOR TO THE UNITED STATES COIN-REGISTER COMPANY, A CORPORATION OF OHIO.

MEANS FOR KEEPING RECORDS OF COIN-REGISTER TAPES.

No. 824,196.

Specification of Letters Patent.

Patented June 26, 1906.

Application filed September 13, 1905. Serial No. 278,207.

To all whom it may concern:

Be it known that I, WILLIAM G. NAGEL, of Toledo, county of Lucas, and State of Ohio, have invented certain new and useful Improvements in Means for Keeping Records of Coin-Register Tapes; and I do hereby declare that the following is a full, clear, and exact description of the invention, which will enable others skilled in the art to which it applies to make and use the same, reference being had to the accompanying drawings, and to the figures of reference marked thereon, which form part of this specification.

This invention relates to and has for its object to provide a means for keeping a record of the severed sections of coin-register tapes.

The invention is particularly devised for the purpose of keeping a record of the collections of telephone pay-stations, although the same is obviously of service wherever tape-registers are employed.

In the registers referred to there are employed rolls of tape having a series of consecutive numbers thereon, the tape being advanced a single number at each operation of the register mechanism, the latter being actuated by the insertion of a coin. The amount paid is indicated by suitable dashes upon the back of the tape. At intervals along the back of the tape there is repeated a number to indicate the register from which the tape has been taken. When the agents of a telephone company make collections at pay-stations where tape-registers are installed, the free end of the tape is severed by drawing over a suitable cutting edge upon the register, the line of severance always being between two consecutive numbers upon the tape. The detached or severed portion of the tape is then turned into the office, together with the money collected. Since each deposit is recorded upon the tape, the amount of money turned in by the collector must correspond with the record thereon. To properly assemble these detached portions or sections of tape and keep them in convenient form for record and ready reference is the object of my invention.

In carrying out the invention I employ a sheet or card of suitable stiff material, such as ordinary cardboard, upon which is printed or otherwise indicated a continuous pathway for the tape, the latter being wound upon the

card in spiral form. I also provide means for securing the ends of the tape-sections together and to the card.

Figure 1 shows a card arranged for the reception of the tape-record, 1 indicating the card, of elongated rectangular form, having the series of spaces or columns 2 slightly inclined to the vertical, these being printed or otherwise indicated on both faces of the card. The columns on one face of the card are indicated by full lines and those on the other face by the dotted lines a, it being observed that the ends of the columns on opposite faces register, the arrangement being such that a continuous pathway of spiral form is provided to receive the record-tape.

The manner of mounting the severed sections of the tape is indicated in Fig. 2, the first severed section of the tape being shown at 3. The upper end of this section of tape is suitably secured by an adhesive to the top of the first column on the left-hand side of the card. To secure the lower end of the severed section, I employ a sticker of paper (shown detached in Fig. 3) having a gummed back and having the face thereof gummed at the ends at 4. The free end of the section 3 of the tape is now secured to the sticker to expose the severed edge 5, and the sticker is then secured to the card. In like manner the next severed section of the tape is secured at its upper end to the sticker to expose its severed edge, the continuation of the tape being shown by the consecutive numbers and also by careful inspection of the severed edges, the latter exactly fitting each other. Upon the sticker are provided suitable spaces for the entry of the date on which a collection was made, the amount of the collection, the number of the consecutive numbers on each severed section, and the name of the collector, the latter being preferably indicated by initials. In this manner the various sections of the tape as they are turned in are conveniently assembled for ready reference. On both faces of the card 1 are also provided a suitable space 6 to show in tabulated form the various data contained on the several stickers. At the top of this space may be indicated the number of the card for the purpose of indexing, the telephone-number, the name of the subscriber, the number of the subscriber or station, and such other data as may be found essential or convenient.

The novelty, utility, and advantages of the herein-described means for keeping a complete and positive record of the collections from tape-registers will be apparent.

5 Although I have specifically described a preferred means for carrying out my invention, I do not desire to be thereby limited, since it is apparent that modifications and changes may be made therein and the invention appropriated in such a way as not to constitute a substantial departure.

Having described my invention, what I claim, and desire to secure by Letters Patent, is—

15 1. In a means for keeping a record of the severed sections of coin-register tapes, a card having a continuous spiral-like pathway for the tape indicated thereon.

20 2. In a means for keeping a record of the severed sections of coin-register tapes, a card having a pathway for the tape indicated on both of its faces and continuous throughout.

25 3. In a means for keeping a record of the severed sections of coin-register tapes, a card provided with a series of columns on both of

its faces, the said columns being slightly inclined and registering at the ends so as to provide a continuous spiral-like pathway for the tape.

4. In a means for keeping a record of the severed sections of coin-register tapes, a card having a continuous pathway for the tape indicated thereon, and a sticker for securing the tape-sections, having a gummed back to adhesively secure the same to the card and 30 having the face thereof gummed at the ends to secure the severed ends of the tape-sections thereto, the face of said sticker being ungummed between the ends adapted to receive the ends of the tape-sections to permit 35 the entry thereon of suitable identifying data, substantially as described.

In testimony that I claim the foregoing as my own I affix my signature in presence of two witnesses.

WILLIAM G. NAGEL.
